JOHN M. COFFIN, OF LEHIGH TOWNSHIP, PENNSYLVANIA.

Design No. 4,215, dated July 12, 1870.

DESIGN FOR A SLATE-FRAME.

The Schedule referred to in these Letters Patent and making part of the same

---

I, JOHN M. COFFIN, of Lehigh Township, Northampton county, Pennsylvania, have invented and produced a new and original Design for School Slate-Frames, of which the following is a specification.

The nature of my design consists in scalloping or curving the sections of the frame contiguous to the rounded corners thereof, so as to bring the outlines of

the scallops a little below the plane of the edge of the frame, as shown.

I claim as my invention—

The design for a school slate frame, as shown.

JOHN M. COFFIN.
